VERNON ROSS AND ERRETT S. RHOADS, OF KANSAS CITY, MISSOURI, ASSIGNEES TO
ROSS RHOADS COMPANY, OF KANSAS CITY, MISSOURI, A CORPORATION OF MIS-
SOURI.

WINDOW FRONT CONSTRUCTION.

Application filed May 9, 1921. Serial No. 487,907.

To all whom it may concern:

Be it known that we, VERNON Ross and ERRETT S. RHOADS, citizens of the United States, and residents of Kansas City, county 5 of Jackson, State of Missouri, have invented a certain new and useful Improvement in Window Front Constructions, of which the following is a complete specification.

This invention relates to store front construction of that general class in which the window lights are held in position under an unyielding pressure, and pertains more especially to that class exemplified in our application No. 399059, filed July 26, 1920, in 10 which the glass-clamping means is hidden, and in which provision is made for the accommodation of glass of different thicknesses.

In the construction adverted to, there is a 20 limit with respect to the thickness of window glass to be accommodated, beyond which it is impracticable to make adjustments without providing a wider molding strip.

Our special object therefore, is to provide 25 a construction which is universal as regards its applicability for practical and efficient use with window glass of all thicknesses, and in which therefore the parts may be standardized and corresponding parts shall be interchangeable. A construction of this character will make for quick, dependable and economical installation by unskilled labor, and minimize the cost of manufacture.

With the object therefore of producing a 35 store front construction which is universal in the respects mentioned, the invention consists in certain novel and useful features of construction and combinations of parts as hereinafter described and claimed; and in 40 order that it may be fully understood reference is to be had to the accompanying drawings, in which:—

Figure 1 is a fragmental sectional perspective view of a store front construction emblematic of the invention.

Figure 2 is a vertical section taken centrally through the clamping member disclosed by Figure 1.

Figure 3 is a fragmentary front view with 50 the molding strip member exposing more of the parts behind it than Figure 1.

Figure 4 is a horizontal section taken on the line IV—IV of Figure 2.

In the said drawings 1 indicates the win-

dow casing and 2 the backing part thereof 55 for the window glass hereinafter identified, and mounted upon and within said casing is a sheet-metal sheathing 3, which sheathing, where it covers the outer face of the backing 2, is provided at suitable intervals with outwardly-protruding spacing portions 4 (one only appearing) to constitute unyielding abutments for the inner face of the window glass, and, in the drawing, it will be noted that the backing 2 projects into the recesses 60 thus formed, although this construction is not essential; and the part 5 of the sheathing which overlaps the backing at the interior side of the window, is beaded as at 6 so that when the window is washed at its inner 65 side, the water will drain outwardly.

The backing portion of the sheathing is also provided with outwardly-protruding portions 7 (one only appearing) corresponding to the portions 4 except in function, as 75 each portion 7 constitutes a guide for a channeled wedge 8 interposed between and bearing against the opposing edge of the window light and the inclosing or outer portion of the sheathing, it being of course understood that strips of lead or equivalent material (not shown) may be directly interposed between the wedges and the window light to minimize chances of fracture of the latter, as customary in this class of invention.

The wedges are tapered at their outer sides or faces so as to function as wedges between the backing portion of the sheathing and certain clamping members for the glass, and hereinafter identified, and their tapered 90 faces are provided with longitudinal slots 9, the material from said slots being bent outward to form stiffening ribs 10 for said faces.

Drawing members, screws 11 in this instance, extend through clamping members 12 and the slots of the wedges and into the backing portion of the window casing, the said clamping members resting at their lower edges on ribs 14 rising from the outer portion of the sheathing, and projecting from the lower edges of said clamping members are flanges 13 which bear against the tapering or wedge faces of the wedges 8. By this arrangement it will be seen that 105 proper longitudinal adjustment of each wedge 8, affects simultaneous outward and upward adjustment of the associated clamp-

ing member on the rib 14, for a purpose hereinafter explained. It will be noted that when the ribs 14 are pressed out of the portion 15, the edge of such portion is drawn out of vertical alinement (see Figures 1 and 2), but not to such extent as to interfere with the proper retention of the molding strip. The clamping members are crimped at 16 to engage and clamp the glass 17 firmly and unyieldingly against the spacing portions 4, and the extremity of each clamping member terminates in a rolled stiffening edge 18 spaced slightly from the glass.

15 The outer edge of the sheathing strip is slightly offset at 19, to provide a narrow space 20, between such edge and the casing 1, corresponding to the space between the window light and the edge 18 of the clamping member.

20 To provide a finish for the store front and completely hide from view the means for securing the window glass in position along each edge thereof, a resilient molding strip 21 is provided, the same being formed with a flange 22 at its lower edge to be slipped into the space 20, and frictionally held therein. At its opposite margin a hook edge 23 is provided to fit over the 30 rolled upper edge 18 of the clamping member and be snapped into the space between the same and the window glass.

25 In practice the lower edge of the molding strip is first secured in place, and then the operator applies inward pressure upon the opposite edge of the molding strip to cause the hook terminal thereof to yield and then snap into the space between the window light and the rolled edge of the clamping member.

30 It will be noted from the above description and by reference to the drawings that the window glass is clamped unyieldingly in position, and that the simultaneous lateral and vertical adjustments of the clamping members to accommodate the thickness of the glass employed, compensate for the slightly different angles which the central portion of the molding strip will occupy as 35 a result of such adjustments, it being understood that the parts are so proportioned that regardless of the degree of outward and upward movement of the clamping members, the upper ends of the same always 40 remains the same distance from the free edge of the portion 19 of the sheathing, due to the change in relative position of the clamp member 12 with respect to the wedge 8 and the rib 14, and hence accurately accommodates the molding strip regardless of its angular relation to the glass, which relation of course changes slightly according to the thickness of the glass used.

45 It will thus be seen that in assembling the parts of the window front, the adjustment

of the clamping members is determined by the longitudinal adjustment of the wedges, the thickness of the glass of course determining the adjustment of the wedges, and likewise the distance between the point 70 where the crimp 16 will engage the glass and the adjacent edge of such glass. The drawing devices are then operated to clamp the glass firmly in place, and finally the molding strip is secured in position. 75

From the above description it will be apparent that changes may be made within the scope of the invention as covered by the appended claims.

80 What we claim is:

1. A store front construction, comprising a window casing inclosing the window glass, a suitable backing for the glass, a slidable wedge within the casing for adjustment to accommodate the thickness of the glass, a 85 rib, and a clamping member engaging the outer face of the glass and the wedge and resting on the rib.

2. A store front construction, comprising a window casing inclosing the window glass, 90 a suitable backing for the glass, a slidable wedge within the casing for adjustment to accommodate the thickness of the glass, a rib, a clamping member engaging the outer face of the glass and the wedge and resting 95 on the rib, and a molding strip within the casing, hiding the clamping and supporting elements of the structure.

3. A store front construction comprising a window casing inclosing the window glass, 100 a suitable backing for the glass, a wedge adjustable to accommodate the thickness of the glass, a clamping plate, means for adjusting the clamping plate against the glass and wedge, and a rib for engagement by the 105 clamping plate to cause the same to shift its point of engagement with the glass, toward or from the adjacent edge thereof, according to the thickness of the glass employed.

4. A store front construction comprising a 110 window casing inclosing the window glass, a suitable backing for the glass, a wedge adjustable to accommodate the thickness of the glass, a clamping plate, means for adjusting the clamping plate against the glass 115 and wedge, a rib for engagement by the clamping plate to cause the same to shift its point of engagement with the glass, toward or from the adjacent edge thereof, according to the thickness of the glass employed, 120 and a molding strip within the casing and detachably secured at its outer edge at a fixed point with respect to the casing and hooked at its opposite edge to the clamping plate at the end thereof in proximity to the 125 face of the glass.

5. A store front construction comprising a window casing inclosing the window glass, a fixed backing for the glass, a rib within the casing, a slidable wedge between the 130

backing and rib, and a clamping member engaging the outer faces of the glass and wedge and resting on said rib.

6. A store front construction comprising

5 a window casing inclosing the window glass, a fixed backing for the glass, a rib within the casing, a slidable wedge between the backing and rib, a clamping member engaging the outer faces of the glass and wedge
10 and resting on said rib, and a molding strip secured within the casing and covering the clamping and supporting elements of the store front.

7. A store front construction comprising
15 a window casing inclosing the window glass and having a fixed backing therefor and also having means for spacing the glass from the backing, and also having a rib, a slidable wedge interposed between the backing and
20 said rib and engaging the edge of the glass and the casing, and a clamping member engaging the glass rib and wedge.

8. A store front construction comprising a window casing inclosing the window glass
25 and having a fixed backing therefor and also having means for spacing the glass from the backing, and also having a rib, a slidable wedge interposed between the backing and said rib and engaging the edge of the glass
30 and the casing, a clamping member engaging the glass, rib and wedge, and a molding strip secured within the window casing outward of the rib and engaging the upper edge of the clamping member.

35 9. A store front construction comprising a window casing inclosing the window glass and having a fixed backing therefor and means for spacing the glass from the backing, and also having a rib, a slidable wedge
40 interposed between the backing and said rib and engaging the edge of the glass and the casing, a clamping member resting on the

rib, and means operable from the exterior of the store front for drawing the clamping member against the glass and wedge.

45

10. A store front construction comprising a window casing inclosing the window glass and having a fixed backing therefor and means for spacing the glass from the backing, a rib fixed with relation to the backing, 50 a longitudinally-slotted wedge engaging the backing and forming a support for the window glass, a clamping member resting on the rib and bearing against the outer face of the window glass and the inclined face of the wedge, and a screw extending through the clamping member and the slot of said wedge and into the backing for drawing the clamping member toward the glass and said wedge.

55

11. A store front construction comprising a window casing including the window glass and having a fixed backing therefor and means for spacing the glass from the backing, a rib fixed with relation to the backing, a longitudinally-slotted wedge engaging said backing and forming a support for the window glass, a clamping member resting on the rib and bearing against the outer face of the window glass and the 65 inclined face of the wedge, a screw extending through the clamping member and the slot of said wedge and into the backing for drawing the clamping member toward the glass and said wedge, and a molding 70 strip fitted in the window casing and engaging the same at one edge and at the other edge to the extremity of the clamping member adjacent the point of engagement of the latter with the glass.

75

80 In witness whereof we hereunto affix our signatures.

VERNON ROSS.
ERRETT S. RHOADS.
